UNITED STATES PATENT OFFICE.

JOSEPH N. BORGLIN, OF SEATTLE, WASHINGTON.

SHIP-LAUNCHING DEVICE.

1,313,786.

Specification of Letters Patent. Patented Aug. 19, 1919.

Application filed November 30, 1918. Serial No. 264,836.

To all whom it may concern:

Be it known that I, JOSEPH N. BORGLIN, a citizen of the United States, residing at Seattle, in the county of King and State 5 of Washington, have invented certain new and useful Improvements in Ship-Launching Devices, of which the following is a specification.

This invention relates to means for launching a ship.

While building a ship, it is worked up upon fixed supports, and when the hull is finished and is to be launched, longitudinal beams are piled on ways each side the supports, and wedges are driven in between the beams to remove the weight from the supports so that the hull may slide of its own weight into the water. The wedges have heretofore been driven in manually and this 20 old method is necessarily slow and expensive.

According to this invention it is proposed to provide a portable power hammer disposed adjacent the sides of a vessel on the ways, and when the hull is to be launched the 25 hammer is moved into position to strike successive blows on the wedges, to quickly and expeditiously separate the beams and elevate the hull from the fixed supports.

The invention also comprehends improvements in the details of construction and arrangement of parts which will be hereinafter described and particularly pointed out in the claims.

In the drawings:—

Figure 1 is an end view conventionally illustrating a ship on the ways, and my improved wedge driving means in operative position.

Fig. 2 is a plan view of the same.

Fig. 3 is a side view of the hammer operating mechanism.

Fig. 4 is a detail cross section of the top of the truck.

Fig. 5 is a detail longitudinal section of 45 the same.

Fig. 6 is a detail view of the hammer.

1 indicates a central fixed support of a ship's way composed of beams piled one on the other, and 2 a hull supported thereon. On 50 each side of the support is a slide 3, which, when the ship is launched is greased, and which is provided with guides 4. Piled on

the slides are beams 5, which extend up to the bottom of the hull of the ship. Interposed between the beams 5, at suitable intervals, are wedges 6, all of usual construction and arrangement.

Alongside the slides, and suitably spaced therefrom, are rails 7, which support trucks 8, carrying the hammers and the operating mechanism therefor. As the mechanism supported on the trucks is identical, but one will be described.

The top of the truck forms a platform 9, which is provided with toothed gibs 10, operating in guideways 11, in the truck frame.

A shaft 12, extends longitudinally through the truck, and has fixed thereto pinions 13, which mesh with the rack teeth on the gibs. The shaft is also provided with a handle 70 14, a ratchet wheel 15, and a pawl 16, co-operating with the ratchet to hold the parts in adjusted position.

Extending from the platform 9, are standards 17, which support a table 18, having 75 guideways 19. Mounted in bearings in a pair of the standards 17, is a crank shaft 20, provided on one end with a fly wheel 21, and on its opposite end with a gear wheel 22.

The crank shaft 20 cooperates with a hammer 23, provided with side flanges 24, which operate in the guideways 19, and on one end of the hammer is a lug 25, disposed in the path of the crank of the shaft 20. One end of a spring 26, is connected to the rear end of the hammer, and the opposite end of said spring is attached to the table, the tension of the spring being such as to withdraw the hammer after the crank has driven it in the opposite direction.

A suitable motor 30, is mounted on the platform to drive the crank shaft. The motor comprises a base 31, crank shaft 32, cylinder, piston connections 33, and oppositely disposed fly wheels 34. On the shaft 32, is 95 a pinion 35, which meshes with the gear wheel 22.

In operation, assume the hull 2 of the ship is to be launched, the trucks are moved on the rails to the desired positions adjacent the wedges 6. Then the shafts 12 are rotated to laterally adjust the platforms 9, to properly space the ends of the wedges. The motors are started, and as the crank shafts

20, contact with the lugs 25, and the springs are placed under tension. Then when the cranks leave the lugs the springs act to cause the hammers to strike the wedges and 5 drive the latter in between the beams 5. Then the trucks are advanced to the next wedges, and back to the first ones operated, each time driving the wedges farther in. As the wedges are gradually driven in, the 10 beams 5 elevate the hull of the ship from the central support 1, and by properly tilting the beams with the wedges, the hull will slide down the ways 3 to the water.

To expedite the operation, there will be 15 several trucks on each side, each truck being used to operate on a specific number or group of wedges.

Each time the truck is moved back to 20 again operate on a wedge, the platform is adjusted to obtain an effective blow, as will be readily understood.

The hammers deliver effective blows on the wedges, as will be readily appreciated.

From the foregoing description, considered with the accompanying drawings, it 25 will be seen that I have provided a simple and effective means for launching a ship. As the trucks can be quickly moved on the rails to act on the various wedges, the opera-

tion can be performed in less time, and more 30 effectively than heretofore.

What I claim is:—

1. Means for launching a ship comprising in combination, keel blocks and launching ways, wedges interposed between the launching ways, tracks arranged parallel with the launching ways, trucks which travel on the tracks, and hammers mounted on the trucks to strike the wedges and drive same in between the launching ways. 35 40

2. Mechanism for launching a ship comprising in combination, launching ways, wedges interposed between the launching ways, tracks parallel with the launching ways, trucks which travel on the tracks, each 45 truck having transverse guideways, a platform on the truck, toothed gibs on the platform, a shaft on the truck, pinions on the shaft to engage the teeth on gibs, a table supported on the platform, a hammer on the 50 table, guides for the hammer, a crank shaft mounted above the table and adapted to engage the hammer, means to return the hammer to drive same against the wedges to force the latter in between the ways, and a motor 55 on the platform to operate the crank shaft.

In testimony whereof I affix my signature.
JOSEPH N. BORGLIN.
